LIP STICK CASE

Clinton E. Marshall, New York, N. Y.

Application July 27, 1934, Serial No. 737,169.

5 Claims. (Cl. 24—11)

This invention relates to lip stick cases and similar articles of manufacture employing elongated tubular caps; and the object of the invention is to provide an improved clip construction for caps of the class described made from a comparatively narrow strip of metal and shaped to be passed through a slit or opening in one wall of the cap and to fit within the side and end walls of a cap to provide a firm mounting of the clip in connection therewith; a further object being to provide means in the form of a rivet or similar coupling device for securing part of the clip to the end wall of the cap; a further object being to provide a clip of the class described, the spring arm portion or clip proper of which is relatively short to be consistent with the size of the article in connection with which it is mounted and to provide means for securely retaining the lip stick device in connection with the wall of a pocket in a pocketbook or in connection with any other support; and with these and other objects in view, the invention consists in a device of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a lip stick device showing a clip thereon.

Fig. 2 is a section on the line 2—2 of Fig. 1 on an enlarged scale; and,

Fig. 3 is a plan view of a part of a strip from which a number of my clip devices are formed, indicating the first blanking and piercing operation.

For the purpose of illustrating one use of my invention or one method of carrying the same into effect, I have indicated in Figs. 1 and 2 of the drawing a lip stick device consisting of a casing 5, in which is mounted a lip stick 6, projecting from the open end of the casing 5 and protected by an elongated thimble-shaped cap 7, the free edge of which seats upon a bead 8 formed on the casing 5, and the closed end 9 being provided with an aperture 10 centrally thereof. The side wall of the cap 7 adjacent the end wall 9 is provided with a slit or opening 11 to facilitate mounting of a clip 12 in connection with said cap.

The clip 12 is made from a narrow strip of

metal or similar material 13 as partially indicated in Fig. 3 of the drawing, and this strip is pierced at intervals to form openings 14 therein and is severed at the points 15 and 16 to form of the strip between the points 15 and 16 a workpiece 17 from which the clip 12 is formed.

In severing the strip at 15 and 16, V-notches 18 may be cut in order to form a pointed or contracted outer end 19 on the resulting clip but the same result may be accomplished by grinding said end, as will be apparent. The strip 13 adjacent the pointed end 19 is curved slightly as seen at 20 to form an article engaging portion and to flare the end 19 outwardly with respect to the wall of the cap 7 to give free admission of an article between the part 20 of the clip and the outer wall of the cap 7. The strip 13 substantially centrally thereof is curved as seen at 21 to give spring action to the end 19, 20 and adjacent the curve 21 is an angular offset 22 which is disposed adjacent the inner surface of the side wall of the cap 7, as clearly seen in Fig. 2.

The other end portion 23 of the clip is bent at right angles to the offset part 22 or to a contour conforming with the closed wall 9 of the cap so as to seat snugly thereon, and the aperture 14 is arranged on the end 23 so as to be in registering alignment with the aperture 10 in the cap to receive a rivet 24 or other coupling member which is passed through the apertures 10 and 14 respectively and then riveted over as seen at 25 to securely retain the clip 12 in position. The inner end of the rivet 24 is preferably tubular in form to facilitate the riveting operation at 25. However, any form of coupling device may be employed to secure the end 23 of the clip 12 to the end wall 9 of the cap.

By virtue of the form and construction of the parts 22 and 23 of the clip 12 and the fact that the aperture or seal 11 is substantially of the same dimensions as the cross section of the strip 13 from which the clip is formed, the clip will be firmly retained in connection with the cap and will provide therefor a very simple, economical and yet strong and durable clip for mounting the lip stick or other device in connection with the wall of a pocket or other support.

In attaching the clip to the cap, the end portion 23 is first passed through the aperture 11 and the clip manipulated to pass the portion 22 through said aperture, after which the clip is moved to bring the parts into the position shown in Fig. 2 of the drawing. By the use of suitable tools, the rivet 24 may be inserted in position and headed to secure the clip in position.

By reason of the construction employed in the clip, no great stress or strain is placed upon the side wall of the cap in the operation of attaching and detaching a device with respect to a support. Any suitable design or ornamentation may be applied to the strip or the outer surface thereof to enhance the appearance thereof. My invention is not limited in its use to the specific structure of device or article of manufacture herein shown and described, the distinctive features of the invention residing in the particular type and method of construction of the clip herein disclosed as well as the method of its mounting in connection with a support.

Having fully described my invention, what I claim as new and desire to secure by Letters Patent, is:

1. A clip for elongated tubular caps of the class described, the end wall of the cap having an aperture and the side wall a narrow opening disposed adjacent said end wall, the clip comprising an elongated metallic strip, one end portion of which is fashioned to form a spring clip disposed outwardly of the wall of said cap, and the other end portion being passed through the opening in the side wall of the cap and bent a number of times to form a part arranged upon the inner surface of the closed end wall of said cap and a part adjacent the inner surface of the side wall of the cap, and means passed through the aperture in the end wall of the cap and engaging that part of the strip adjacent said end wall for retaining the clip against displacement from the cap.

2. A clip for elongated tubular caps of the class described, the end wall of the cap having an aperture and the side wall a narrow opening disposed adjacent said end wall, the clip comprising an elongated metallic strip, one end portion of which is fashioned to form a spring clip disposed outwardly of the wall of said cap, the other end portion being passed through the opening in the side wall of the cap and bent a number of times to form a part arranged upon the inner surface of the closed end wall of said cap and a part adjacent the inner surface of the side wall of the cap, means passed through the aperture in the end wall of the cap and engaging that part of the strip adjacent said end wall for retaining the clip against displacement from the cap, and said clip being formed from a strip of metal of the same dimensions substantially throughout the length thereof, the free end of the clip proper being outwardly flared and substantially pointed.

3. A clip for tubular members of the class described comprising an elongated strip of material of substantially the same width throughout its length, one end portion of the strip being bent to form two adjacent parts disposed substantially at right angles to each other, one of said parts forming one end of the clip and being longer than the other adjacent part and that part of the strip adjacent the second named part being bent and curved to form of the other end portion of the strip a spring clip, said last named end portion terminating in an outwardly flared end, the first named end being apertured, the first named end portion of the strip forming the mounting end of said clip, a tubular member having in one wall thereof an aperture through which the mounting end portion of the clip is passed, said tubular member having a closed end wall, and means passed through said end wall and the aperture in the first named end part for securing said part to the end wall of said tubular member.

4. The combination with a thimble-shaped cap, the closed end wall of which is provided with an aperture and the side wall thereof with an elongated slot adjacent said end wall, of a clip comprising a mounting end portion composed of angular parts, one disposed adjacent the inner surface of the end wall of said cap and apertured to register with the aperture in said wall and the other upon the inner surface of the side wall of the cap, the last named part extending through the slit in said wall and terminating in an outwardly and inwardly curved spring clip disposed on the outer surface of the side wall of said cap.

5. The combination with a thimble-shaped cap, the closed end wall of which is provided with an aperture and the side wall thereof with an elongated slot adjacent said end wall, of a clip comprising a mounting end portion composed of angular parts, one disposed adjacent the inner surface of the end wall of said cap and apertured to register with the aperture in said wall and the other upon the inner surface of the side wall of the cap, the last named part extending through the slit in said wall and terminating in an outwardly and inwardly curved spring clip disposed on the outer surface of the side wall of said cap, and means passed through the apertures in said end wall and that part of the mounting end of the clip adjacent said wall for securing the clip against displacement from the cap.

CLINTON E. MARSHALL.
